BUILDING BLOCK LIFT

David A. Allen, Mount Vernon, Ohio

Application September 22, 1948, Serial No. 50,462

1 Claim. (Cl. 294—15)

1

This invention relates to new and useful improvements and structural refinement in lifts for building blocks, and the principal object of the invention is to facilitate convenient lifting and carrying of building blocks, as well as installation thereof in an appropriate position in the building structure.

This object is achieved by the provision of what may be referred to as a lifting tool, the same being readily engageable with and disengageable from the building blocks and including a handle which may be easily gripped while the blocks are being lifted or carried.

An important feature of the invention resides in the particular configuration of the tool, more specifically, in the particular configuration of the block engaging members of the tool, which assure that the blocks are firmly and securely gripped but at the same time, which permit the tool to be readily disengaged from the blocks, when so desired.

An important advantage of the invention lies in its simplicity of construction, in its pleasing appearance, and in its adaptability to economical manufacture.

Another advantage of the invention resides in its ability to prevent injury to the worker's hands, or damage to gloves which he may be wearing while handling rough-surfaced blocks.

With the above more important objects and features in view and such other objects and features as may become apparent as this specification proceeds, the invention consists essentially of the arrangement and construction of parts as illustrated in the accompanying drawings, in which:

Figure 1 is a perspective view of a block lift embodying the principal features of the invention;

Figure 2 is a cross sectional view, taken substantially in the plane of the line 2—2 in Figure 1;

Figure 3 is a fragmentary cross sectional view, taken substantially in the plane of the line 3—3 in Figure 2, and

Figure 4 is a cross sectional view, taken substantially in the plane of the line 4—4 in Figure 2.

Like characters of reference are employed to designate like parts in the specification and throughout the several views.

Referring now to the accompanying drawings in detail, the invention consists of a building block lifting tool designated generally by the reference character 10, the same preferably

5 being formed integrally from one piece of material by casting, or the like, and embodying in its construction an elongated body 12 which tapers from one end thereof to the other, the tapered end portion of the body being formed with a plurality of transversely extending, finger receiving grooves 14 and constituting what may be referred to as a handle 16 (see Figure 1).

10 The remaining end portion of the body 12 is formed integrally with an arcuate block engaging blade 18 which extends in a substantially perpendicular direction from the body, and is best shown in Figures 1 and 3. The blade 18 includes a block engaging surface 20 formed with a central, longitudinal rib 22 and with longitudinal concavities 24 at the sides of the rib, while the relatively opposite side of the blade is formed integrally with a longitudinal reinforcing web 26. The longitudinal rib 22 and concavities 24 terminate short of or at the widened bottom edge of the blade 18 with the bottom edge of the blade 18 being substantially straight as shown in Figs. 1 and 4.

15 25 A coacting block-engaging protuberance 28 is formed integrally on an intermediate portion of the body 12, the configuration of the protuberance being best illustrated in the accompanying Figure 1, wherein it will be noted that the protuberance is spaced with respect to the blade 18 and that a portion of the body 12 between the protuberance and the blade forms an arcuate edge 30 which "connects" the protuberance to the blade, substantially as shown.

20 30 35 It will be noted that the protuberance 28 includes an outer end portion 32 which is set away from the blade 18 so as to provide block receiving sockets of different widths between the protuberance and the blade, the respective widths of the sockets being indicated diagrammatically at 34, 36 in Figure 3. The invention is, of course, intended for use in association with building blocks provided with open "cells" separated by transverse intermediate and end portions of the blocks, and when the tool is placed in use, it is applied to the blocks so that the protuberance 28 is disposed in one of the end "cells" while the blade 18 is disposed on the outside of the block, with the handle 16 extending toward the center of the block so that when the block is lifted, the lifting force is applied centrally and convenient carrying is thereby facilitated. The different "widths" 34, 36 of the block receiving sockets facilitate, of course, the use of the tool in association with blocks having different wall thicknesses, and it is to be noted that the blade 18,

particularly at the free end portion thereof, is of substantially greater width than the body 12, whereby the blade effectively stabilizes the blocks being carried against possible lateral swinging movement.

In order to assure light construction, an intermediate portion of the body 12 may be provided in the sides thereof with elongated recesses as indicated at 38, but to assure sturdiness, a longitudinally extending reinforcing rib 40 is provided on the body 12, substantially as shown.

While in the foregoing there has been shown and described the preferred embodiment of this invention, it is to be understood that minor changes in the details of construction and arrangement of parts may be resorted to without departing from the spirit and scope of the invention, as claimed.

Having described the invention, what is claimed as new is:

A building block lifting tool formed integrally from one piece of material and comprising an elongated body tapering from one end thereof to the other, the smaller end portion of said body being formed with transverse finger-receiving grooves and constituting a handle, an arcuate block-engaging blade extending in a substantially perpendicular direction from the larger end portion of said body, said blade having a

5 block-engaging inner surface extending transversely of said body which is formed with a central longitudinal rib and with longitudinal concavities at the sides of said rib, and a coacting block-engaging protuberance extending from an intermediate portion of said body having a cooperating block engaging surface in spaced opposing relation to said blade, a portion of said body between said protuberance and said blade forming an arcuate edge connecting said protuberance to said blade, and said protuberance having the outer end portion of its block engaging surface stepped away from said blade to provide block-receiving sockets of different widths between said protuberance and said blade.
